(57) **CLAIM**

The ornamental design for a slam latch, as shown and described.

DESCRIPTION

FIG. 1 is a perspective view of a slam latch showing our new design thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is perspective view thereof, with the slam latch shown in open position and its environmental use.

The broken line environment is for illustrative purpose only and forms no part of the claimed design.
